UNITED STATES PATENT OFFICE.

ALBERT DUROT, OF MANCHESTER, ENGLAND, ASSIGNOR TO SIR JAMES FARMER & SONS LIMITED, OF SALFORD, MANCHESTER, ENGLAND.

CLOTH PLAITING OR PILING MACHINE.

1,468,083.

Specification of Letters Patent. Patented Feb. 28, 1922.

Application filed December 7, 1920. Serial No. 428,988.

(GRANTED UNDER THE PROVISIONS OF THE ACT OF MARCH 3, 1921, 41 STAT. L., 1313.)

To all whom it may concern:

Be it known that I, ALBERT DUROT, a citizen of France, and resident of Adelphi Iron-works, Salford, Manchester, in the county of 5 Lancaster, England, have invented certain new and useful Improvements in Cloth Plaiting or Piling Machines, (for which I have filed an application in Great Britain Aug. 31, 1916, Patent No. 104,118,) of which 10 the following is a specification.

This invention relates to cloth plaiting or piling machines.

Heretofore it has been proposed to plait or pile cloth in rope form by passing it 15 through a guide-eye traversed back and forth across and over a winch reciprocated both along and across the machine.

The object of the invention is to provide an improved construction of piling machine 20 and it consists in the combination with a guide eye cross traversed by a continuously rotating right and left hand screw and supported independently of the winch carriage, 25 of a winch extending the full width of the machine and having a reciprocatory movement imparted thereto by endless moving chains carrying lugs projecting into elongated slots in the winch carriage, the cloth from the guide eye passing over a drawing 30 roller or drum on its way to the winch.

Referring to the accompanying explanatory drawing:—

Figure 1 is an end elevation and Figure 2 a plan view of a cloth plaiting or piling machine constructed in accordance with this 35 invention. In Figure 2 the guide eye is shown in full lines for the sake of clearness.

The same reference letters in the two views indicate the same parts.

40 The cloth in rope form is passed through a pot or other guide eye *a* which is supported on an arm *b* traversed back and forth across the machine in the known manner by a right and left hand rotating screwed rod

c. The cloth *d* from said guide passes over 45 a drawing roller or drum *a'* to a winch *e* which is of any usual form extending from side to side of the machine and adapted to give the cloth rope as it descends therefrom a wave-like motion for piling purposes. 50 The winch carriage or frame *f* runs on rollers *g* upon suitable rails or angle irons *h* and the winch is rotated by a belt *i* running round the winch pulley *j* over tension rollers *k* on the winch frame and over pulleys *m*, 55 one at each end of the machine.

The longitudinal traverse or reciprocation of the winch frame *f* is effected by two endless chains *n*, running over sprocket wheels *o* supported by the rails or angle irons *h* 60 aforesaid. A lug-like part *p* projects from each chain and each lug enters an elongated slot *q* in a side member of the winch frame *f*. Thus, as the chains are moved, they carry the winch frame with them. As the 65 lugs pass round the chain sprocket wheels *o*, they move along the slots *q* aforesaid either rising or falling in same, and so come into position to move the frame in a reverse direction. 70

Having now described my invention what I claim as new and desire to secure by Letters Patent is:—

In cloth plaiting or piling machines, having a guide eye traversable back and forth 75 across the machine, in combination with a winch frame, a winch extending the full width of the machine, means for rotating said winch, vertical slots in the winch frame, chains with projections entering said slots 80 for traversing the winch frame back and forth in the machine, and a drawing roller or drum feeding the cloth to said winch, as set forth.

In testimony whereof I have signed my 85 name to this specification.

ALBERT DUROT.
